LOCK-ACTUATOR FOR TOTAL-PROOF DEVICES ON COMPUTING-MACHINES.

1,274,730.

Specification of Letters Patent.

Patented Aug. 6, 1918.

Application filed May 31, 1916. Serial No. 100,989.

To all whom it may concern:

Be it known that I, HENRY N. MCKAY, a citizen of the United States, residing at Oakland, in the county of Alameda and State of California, have invented new and useful Improvements in Lock-Actuators for Total-Proof Devices on Computing-Machines, of which the following is a specification.

10 This invention relates to a lock actuator for total proof devices on computing machines; this application being in the nature of a division of my co-pending case, entitled Total proof device for adding mechanism, filed March 10, 1915, Serial No. 13,332.

The purpose of this device is to provide a mechanism for actuating a locking device which is operable to lock certain parts of 20 the typewriter mechanism and computing mechanism when an incorrect total is transcribed from the totalizer.

At present, in key actuated computing machines which "clear" back to zero by 25 direct subtraction or complementary addition, it is possible for an operator, by mistake to copy a wrong total on the paper, even though the correct total be shown in the totalizer and then to proceed with a 30 new computation without noting the error. Any digits remaining in the totalizer after such error, cause the next computation to show a wrong result, in this manner creating a double error. Many mistakes are thus 35 made since accuracy of work depends upon the skill or care of the operator only. In other words, correctness depends on a variable human element.

The object of the present invention is to 40 provide means for locking the typewriter mechanism or the attached computing mechanism against further operation when a total shown in a totalizer of the computing machine is not transcribed exactly as it is shown, and particularly to provide a lock actuator operable by or in conjunction with a totalizer for operating the locking mechanism.

Further objects will hereinafter appear.

The invention consists of the parts and

the combination and construction of parts as hereinafter more fully described and claimed, having reference to the accompanying drawings, in which—

Figure 1 is a front elevation of a fragment of a typewriting computing machine with the invention applied, and showing a totalizer attached to the carriage.

Fig. 2 is a plan view.

Fig. 3 is an end elevation of the setting levers.

Fig. 4 is a detail sectional view of the locking dog and its immediately related gear wheel.

Fig. 5 is an enlarged side view of the dog and the transmission gears.

Fig. 6 is a detail face and sectional view of the gears.

The lock actuator illustrated in Fig. 5 is in this instance provided for the purpose 70 of coöperating with a stationary detent 12 for the purpose of locking the carriage between spaces, in which position the numeral keys are not operable. This locking of the carriage takes place when a total shown in 75 the totalizer on the computing machine is not transcribed exactly as it is shown. The lock actuator is however, capable of coöperation with a great variety of locking and signaling mechanisms shown in my co-pending application. For instance, it is possible when a total shown in the totalizer of a computing machine is not transcribed exactly as shown, to lock the carriage 80 against movement as illustrated in the present application. Again, it is possible to lock both the numeral and letter keys; furthermore, to lock the totalizer actuating mechanism and also to cause visible or audible signals to be operated, or to operate a combination of these locks and signals, as fully 85 described in my co-pending application, Serial No. 13,332.

The lock actuator, briefly described, is produced by forming one or more notches as 95 indicated at 7', in the periphery of the transmission or carrying gears 7 carried by the computing mechanism or totalizer 8. These notches have fixed positions with relation to the zeros of the coacting numeral 100

wheels indicated at 10, carried by the totalizer, and will all form an alinement with each other when all the numeral wheels are turned to zero position. They will simultaneously form an alinement with the blocking dog or detent indicated at 12 and will therefore pass over same when all the numeral wheels show zero position. The zero position of the numeral wheels is only assumed when the total is correctly transcribed, and the notches 7' will therefore be in alinement with the detent 12, thus permitting the carriage and the totalizer mounted thereon, to pass freely across the detent 12 without stopping or locking the carriage. If a total is incorrectly described, it can easily be seen that one or more digits will remain in the numeral wheels, as these have not been completely returned to the zero position. It therefore also follows that all the deep notches 7' will not be in alinement and that as the carriage and totalizer move across the detent 12, an interference or stop will be made when the shallow teeth of an accumulating gear 7, which has not been returned to proper position, comes into engagement or alinement with the detent 12. The carriage and totalizer with connected mechanism will therefore be locked and the operator will necessarily have to make the necessary corrections to permit the free passage of the carriage and connected totalizer. From the foregoing description, it can be seen that the lock actuator is produced by forming one or more deep notches in the periphery of each of the accumulating gears 7 carried by the totalizer, and as these notches have fixed positions with relation to the zeroes on the numeral wheels, it can readily be seen that it will be impossible for the carriage and totalizer to pass the detent 12 before the zero position of all the numeral wheels and an alinement of deep notches is secured.

One must naturally assume that the average work performed by an operator is correct and that wrong transcriptions of totals are more or less infrequent. The normal function of the notches 7' is therefore to pass over the detent 12 and not to engage with same. They may therefore be termed the pass-over notches. The particular mechanism employed in the present instance for co-operation in connection with the lock actuator will be as follows:

In Fig. 1, 2 represents a typewriter digit key lever, the key button 3 being indicated in dotted lines, and of which levers the usual complement is provided but not here shown. The key lever 2 is connected by a link 4 to and for operating a mechanism indicated generally at 5 and which has for its prime function the rotation of a master pinion 6; each digit key being effective through said mechanism to turn the pinion a prede-

termined degree for the rotation of transmission gears 7 of a computing device indicated generally at 8. The computer 8 is here shown as adjustably attached to a portion 9 of a typewriting machine carriage. 70

Operation of any of the digit keys 2 serves to actuate the transmitting mechanism 5 and a gear 7 in mesh with the master wheel 6, so that the corresponding value will be indicated at the computer by its 75 numeral wheels 10.

Assuming that a column has been written and totalized by the machine and the operator wishes to transcribe the total and at the same time clear the computer, then, in the 80 type of machine here shown, he, or she, will depress a shift or subtract lever 11 of the mechanism 5 and which simply changes the direction of rotation of the master wheel 6. Thereupon, as the digit keys are depressed 85 the master wheel resets the numeral wheels 10 to zero, provided the proper keys are struck.

It is to check up and make the correct key operation compulsory during transcription 90 of totals that I have devised my present invention.

The device consists first, of a blocking dog 12 located in position so as to project into the normal tooth notches of any of the transmission gear wheels 7 of the computing totalizer 8, the object of which dog is to prevent the passage across it of any totalizer notch of less than a given capacity; second, of totalizer transmission gear wheels 7 so cut that certain notches 7' shall be wide and deep enough to permit passage of the blocking dog, and all other notches shall be too small to permit its passage, the object of which arrangement is to allow the blocking dog to pass only when certain predetermined numerals are shown in the number wheels of the totalizer; and third, of a means to control the blocking dog so as to release it to an operative position and withdraw it to 110 an inoperative position, as required.

The blocking dog 12 is mounted on a pivot 13, and provided with a spring 14, the tendency of which is to keep the dog extended in operative position. The blocking dog is located in a sequent position with reference to the master or actuator wheel 6 of the adding or subtracting mechanism, so that it must enter a given gear wheel 7 or be passed by a given gear wheel 7, as soon as that gear wheel has passed or been passed by the actuator wheel. The dog is located at a distance of less than a typewriter space from the actuator wheel in order that if the passing notch 7' is too small to clear the dog 12, the movement of the carriage of the typewriter will be arrested before it has moved a full space, thus stopping the carriage between two normal points of rest, and causing the numeral keys of the typewriter 130

to be locked against operation through the regular mechanism provided for that purpose in such machines.

- The blocking dog 12 is connected with the actuating mechanism 5 of the adding or subtracting attachment or mechanism by means of an arm 15 and a cam 16, in such a manner as to cause the dog, when in operative position, to be depressed by each stroke of 10 a numeral key, when adding or subtracting, a sufficient distance to disengage the dog completely from the totalizer gears, and in such a manner also as to cause the dog to be released to resume its operative position 15 after the master wheel of the actuator has ceased to move, and before the typewriter carriage is released by the typewriter escapement to move the next space or point of rest. The object of this disengagement is to 20 prevent the presence of the dog in any gear wheel from obstructing the normal turning of the gear.

The blocking dog is beveled at 12', Fig. 6, in such a manner as to be self-depressing 25 when the totalizer passes or is passed in returning the typewriter carriage, and so permit passage without obstruction regardless of the position of the gear wheel notches.

The specially cut totalizer gear wheels 30 7 which engage with the master wheel 6 of the adding mechanism and with the blocking dog 12, are cut in the following manner for all machines with adding and subtracting mechanism which clear or bring the totalizer 8 back to zero, when a total is copied, by direct subtraction.

(a) All notches 7' in the transmission gear wheels 7 which shall be in line with the blocking dog 12 at the same time that 40 any zero is shown in the corresponding number wheels 10 of the totalizer 8 are cut deeper or wider than the usual or standard tooth notches of the gears, to a sufficient extent to permit the passage of the dog, at all 45 times.

(b) All notches which shall be in line with the blocking dog 12 at the same time that any figure nine is shown in the corresponding number wheels of the totalizer 50 7^a are cut obliquely or inclined on the face 7^a so as to be of their original depth and width on the side first reached by or reaching the blocking dog, Fig. 6; the notches increasing in depth or width or both until, on 55 the opposite side of the gear wheel, they reach the capacity of the full sized escapement, or zero notches described above.

For adding typewriters that clear the totalizer in copying a total by means of the 60 process of complementary addition or "indirect" subtraction, the totalizer gear wheels which engage the master wheel and the blocking dog are specially cut or notched as follows, to-wit:

(c) All notches which shall be in line

with the blocking dog at the same time that any figure nine is shown in the corresponding number wheels of the totalizer are cut deep or wide enough to permit free passage of the dog, at all times.

(d) All notches which shall be in line with the blocking dog at the same time that any zero is shown in the corresponding number wheels of the totalizer are cut obliquely or inclined in the manner described under (b) above, with the exception of the last gear wheel reached by or reaching the actuator wheel, in which last wheel any notches which shall be in line with the dog when a zero is shown in the corresponding number wheel are cut to permit free passage of the dog at all times.

In either type of machine, when any totalizer gear wheel 7 is a double gear, as in Fig. 5, having a left-hand gear wheel to occupy a "decimal point" or "comma space" and act as a "carry-over" gear, all notches 7^b in the "carry-over" gear, which occupies the decimal point or "comma space" are cut to a capacity to permit the free passage of the blocking dog at all times, since no arrest of the carriage is desired at such points.

The control mechanism for rendering the blocking dog inoperative is shown as consisting of a plunger rod 17 mounted on the frame of the typewriter or actuator mechanism, beveled at 18 on the end nearest the dog and having a pin 19 at the opposite end engaging a slotted cam lever 20, which is equipped with a spring 21 tending to 95 maintain said lever at rest position. The plunger rod is so located, and the slot in the cam so constructed, that when the cam lever, here called the "total proof lever" is at rest or upper position, the beveled end of the rod is engaged with the blocking dog 12, retaining it in a depressed, inoperative position, Fig. 4. When the "total proof" or cam lever is depressed, it withdraws the end 18 of the plunger rod from engagement 100 with the blocking dog, permitting the dog to be tipped up by its spring to its operative position.

The "total proof lever" is superimposed on the regular "subtract" lever 11 of the machine when there is one, and is designed to be caught when depressed, under the latch 11' of the subtract lever or under a latch of its own, until subsequently released.

The operation of the above described device on an adding and subtracting typewriter is as follows:

When an addition has been completed and it is desired to copy the total shown in the totalizer, the operator depresses the "total proof lever" 20, which carries down the "subtract lever" 11 of the machine, and simultaneously releases into operative position the blocking dog 12, which then extends into position to engage with the totalizer 125 130

4 gear wheel tooth notches. The operator then tabulates, or moves the typewriter carriage forward until the actuator wheel is in the first space in the totalizer, the number 5 wheel of which is occupied by a numeral other than zero. The blocking dog 12 permits this forward movement as far as the first space so occupied, because the gear notches 7' in line with it in any precedent 10 spaces occupied by zeros are cut to permit its free passage. When the actuator wheel 6 comes to rest in the first wheel occupied by a numeral other than zero, the dog 12 is in a sequent position in the previous wheel 15 passed, and is less than a full space from the actuator wheel.

The operator then strikes the numeral key 2 of the typewriter, corresponding to the initial figure of the total to be copied. If 20 the correct key is struck, the actuator wheel, turning in the reverse or subtract direction, subtracts the figure shown in that number wheel 10 of the totalizer, bringing the number wheel back exactly to zero, and therefore 25 bringing a zero notch 7' or large capacity notch, opposite the blocking dog, and as the carriage is released to move forward to its next operating space there is no obstruction of its movement by the dog. If the 30 wrong typewriter numeral key is struck, be it greater or less than the figure shown previously in the corresponding numeral wheel of the totalizer, the number wheel will not be brought to zero and one of the small capacity notches will be in line with the blocking dog. Therefore as the carriage of the 35 typewriter moves forward toward its next operating space, the entry of the blocking dog into the gear wheel just operated is 40 impossible because of the small notch, the dog catches on and blocks the passage of the gear 7, the carriage is arrested between operating spaces, and the numeral keys of the typewriter are rendered inoperable, by the 45 regular locking system of the typewriter adding machine. The operator is informed of the error on attempting to depress the next numeral key in the effect to complete the transcription of the total. It is then 50 necessary to return the carriage to the previous space in which the error was made, and correct the error, and when a zero is correctly shown in that number wheel the transcription may be continued.

55 When the numeral key struck in error is greater than the figure shown in the corresponding number wheel, the result is an over-subtraction, in which case all preceding number wheels of the totalizer are occupied 60 by nines. When this occurs the blocking dog, (which was depressed during the movement of the actuator wheel as previously described) when it rises, enters the obliquely cut notches 7', which are in line with the 65 dog whenever a nine is shown in a number

wheel, and blocks against the small capacity notch in the wheel just misoperated in. The oblique cutting of these "nine" notches leaves the side of the notch first reaching or reached by the blocking dog of a size small enough to obstruct the passage of the dog when a nine is left in a number wheel by error, beveled so that the dog may be raised to engage the wheel adjacent to the higher point of bevel.

If the operator neglects to release the total proof lever and with it the subtract lever, before proceeding with the next addition, the first numeral key struck other than zero, will bring a numeral into the number wheel 80 corresponding and a small capacity notch 7' in line with the blocking dog 12, thereby causing the carriage to be arrested between operating spaces, and so lock the numeral keys of the typewriter against further operation until the above mentioned levers are restored to the correct position for addition.

When the typewriter adding machine on which this device is used is a machine which clears or brings the totalizer back to zero by 90 the process known as complementary addition, the operation of the device is similar in principle to the above, save that since this method of clearing, correctly performed, requires that "all number wheels of the totalizer be brought to nines except the last, which must be brought to ten, thus clearing the preceding nines to zero and so clearing the totalizer, the notches are so arranged that when this order is exactly followed 95 there is no obstruction and no lock, but that when an error is made and this order is not followed, there shall be an arrest of the carriage and consequent lock similar to that described above, notifying the operator of the 100 mistake. Since in these machines when too small a numeral is struck, or too large a complement added in any wheel, all previous number wheels are brought to zeros in 105 place of nines, the obliquely cut notches are 110 therefore located to come in line with the lock dog when zeros are shown in the number wheels, for the same purpose, and with the same general result as described above for oblique notches.

115 The same arrest of carriage, locking, and consequent notification of error are produced in this type of machine when it is neglected to return the total proof lever to the correct position for addition as are described above for the other type of machine, and in the same general manner.

A third advantage of the device is that it prevents tabulating or moving the typewriter carriage too far forward into a totalizer when a total is to be copied, in which event the transcription would commence at a wrong point.

125 This result is produced because the blocking dog cannot pass any gear wheel, the 130

number wheel of which is occupied by a figure other than zero. The effort to make it do so will cause the arrest of carriage locking of keys, and consequent notification of 5 error described above.

This invention is adapted to operate on, or be used with any typewriter adding machine and any typewriter adding and subtracting machine which operates by means 10 of a stationary actuating mechanism attached to or located on the frame of the machine, and a moving totalizer attached to or connected with the carriage of the machine; or on any above-mentioned machine which 15 operates by means of a stationary totalizer attached to or built on the frame of the machine, and a moving actuating mechanism attached to or connected with the carriage of the machine.

20 Having thus described my invention, what I claim and desire to secure by Letters Patent is—

1. In a totalizer, the combination with a plurality of number wheels, of a plurality of 25 carrying gears adapted to drive said number wheels, a gear adapted to drive any of said carrying gears and a deep notch between certain of the teeth of said carrying gears, said notch having a greater depth than the 30 remaining interdental notches and being so shaped as to not interfere with the driving of said number wheels by said carrying gears.

2. In a totalizer, the combination with a 35 plurality of number wheels, of a plurality of carrying gears adapted to drive said number wheels, a gear adapted to drive any of said carrying gears, and a plurality of deep notches between certain of the teeth of said 40 carrying gears, said notches having a greater depth than the remaining interdental notches and being so shaped as to not interfere with the driving of said number wheels by said carrying gears.

45 3. In a totalizer, the combination with a plurality of number wheels, of a plurality of carrying gears adapted to drive said number wheels, a gear adapted to drive any of said carrying gears, and a deep notch between 50 certain of the teeth of each of said carrying gears, said notch having a greater depth than the remaining interdental spaces

and being shaped so as to not interfere with the driving of said number wheels by said carrying gears, said notch being further so positioned that the notches on all the carrying gears will form an alinement when the number wheels bear certain predetermined relations to each other.

4. In a totalizer, the combination with a 60 plurality of number wheels, of a plurality of carrying gears adapted to drive said number wheels, a gear adapted to drive any of said carrying gears, and a deep notch between certain of the teeth of each of said carrying 65 gears, said notch having a greater depth than the remaining interdental spaces and being shaped so as to not interfere with the driving of said number wheels by said carrying gears, said notches being further so positioned as to form an alinement whenever the number wheels stand at zero.

5. In a totalizer, the combination of a numeral wheel, a computing gear wheel adapted to drive said numeral wheel by 75 means of gear teeth, said computing wheel having certain of the spaces between its teeth deeper than the remaining spaces, said deep spaces being so located as to occupy a certain predetermined relation with the position of said number wheel, whereby the same gear may be used both for driving said number wheel and determining when said number wheel stands at zero.

6. In a totalizer, the combination of a 80 number wheel, a computing gear wheel adapted to drive said number wheel, a deep notch between certain of the teeth of said computing wheel, said deep notch being so positioned as not to interfere with the normal driving of said numeral wheel by said computing gear, and also to keep a certain position when said numeral wheel stands at zero, whereby the same gear may be used both for driving said numeral wheel and 85 determining the zero position thereof.

In testimony whereof I have hereunto set my hand in the presence of two subscribing witnesses.
